UNITED STATES PATENT OFFICE

EARLE S. MACPHERSON, OF DETROIT, MICHIGAN, ASSIGNOR TO HUPP MOTOR CAR CORPORATION, OF DETROIT, MICHIGAN, A CORPORATION OF VIRGINIA

DESIGN FOR AN AUTOMOBILE

Application filed June 22, 1931. Serial No. 40,291. Term of patent 7 years.

To all whom it may concern:

Be it known that I, EARLE S. MACPHERSON, a citizen of the United States of America, residing at Detroit, in the county of Wayne and State of Michigan, have invented a certain new, original, and ornamental Design for an Automobile, of which the following is a specification, reference being had therein to the accompanying drawings forming a part thereof, wherein:

Figure 1 is a side elevational view of an automobile illustrating my new design; and

Figure 2 is a top plan view of the automobile illustrated in Figure 1.

The dominant feature of my design consists in the inclination of the visible dash line and rear edges of the hood to correspond substantially to the inclination of the front body pillars while having the former spaced from the latter.

I claim:

The ornamental design for an automobile substantially as shown and described.

EARLE S. MACPHERSON.
